United States Patent Office

Des. 207,725
Patented May 23, 1967

207,725

CUP OR SIMILAR ARTICLE

Frank J. Benes, Lancaster, Ohio, assignor to Anchor
Hocking Glass Corporation, Lancaster, Ohio, a corporation of Delaware

Filed June 28, 1966, Ser. No. 2,845

Term of patent 14 years

(Cl. D44—9)

FIG. 1 is a side elevational view of a cup or similar article showing my new design;

FIG. 2 is a top plan view of the cup shown in FIG. 1; and

FIG. 3 is a rear elevational view of the cup shown in FIG. 1.

I claim:

The ornamental design for a cup or similar article, substantially as shown.
